UNITED STATES PATENT OFFICE

WILLIAM E. TETER, OF WOOD RIVER, ILLINOIS

BUBBLE TOWER

Application filed February 18, 1928. Serial No. 255,294.

This invention relates to dephlegmating or bubble towers such as are used in the production of gasoline or the like, and has more particular reference to towers of the type described in the U. S. patent to F. E. Gilmore, No. 1,598,772, dated Sept. 7, 1926, wherein warm vapors containing gasoline rise in the tower through a series of bubble trays placed transversely of the tower, the vapors being partially condensed as they ascend.

An important object of the present invention is to provide a bubble tower having that portion of the same, above the portion in which the liquid oil is maintained at a given level, laterally or horizontally enlarged, thereby permitting expansion of the vapors, providing for an increase in the capacity of the tower, and minimizing the likelihood of carrying over those substances which impart poor color and gravity to the product.

A further object is to generally simplify and improve the construction and arrangement of the bubble trays, as well as the means for conducting the excess oil downwardly from one bubble tray to another.

A still further object is to provide means for effectively retarding the ascending vapors and preventing excessive bubbling of the oil in the bubble trays.

Other objects will appear as the nature of the invention is better understood, and the same consists in the novel form, combination and arrangement of parts hereinafter more fully described, shown in the accompanying drawings and claimed.

In the drawings:

Figure 1 is a central vertical sectional view of a bubble tower constructed in accordance with the present invention.

Figure 2 is a horizontal section on line 2-2 of Figure 1.

Figure 3 is a horizontal section on line 3-3 of Figure 1.

Figure 4 is a horizontal section on line 4-4 of Figure 1.

Figure 5 is an enlarged fragmentary section on line 5-5 of Figure 4; and

Figure 6 is an enlarged perspective view of one of the devices for conducting the excess oil downwardly from the bubble trays.

Referring more in detail to the drawings, the present tower embodies an upright elongated casing having a lower portion 5 and a laterally or horizontally enlarged upper portion 6. Heated oil is introduced into the lower portion 5 of the tower casing near the bottom thereof through a pipe 7, and excess oil and residue is suitably drawn from the lower portion of the tower casing through a pipe 8 so that the heated oil is maintained at a predetermined level in said lower portion of the tower casing. Leading from the top of the tower casing is a pipe 9 by which the treated vapors are conducted to a condenser.

A series of bubble trays are placed transversely of the tower casing so as to partition the latter, one of the trays being relatively small and placed in the top of the lower portion 5 of the tower casing, and the remaining trays being larger and placed in spaced relation one above another in the enlarged upper portion 6 of the tower casing, as clearly shown in Figure 1.

Each bubble tray embodies a pan 10 whose bottom is provided with apertures in which are mounted tubular vapor risers 11, of inverted J-shape, which extend upwardly for a distance nearly corresponding to the depth at which it is desired to have the gasoline accumulate, and then extending downwardly to a point above but adjacent the bottom of the pan. Vapors being treated in the tower, therefore, pass through the vapor risers and through the accumulated gasoline to the next tray above, where the same course is repeated. The rims of the pans 10 are of greater height than the vapor risers 11, and covering and resting upon the upper edges of these rims are perforated plates 12 which retard the ascending vapors and prevent excessive bubbling of the oil or gasoline in the pan.

Each plate 12 has a central opening in which is secured the upper end of a tube 13 which projects downwardly through the associated or adjacent pan 10 and has downwardly diverging branches 14. The branches 14 of the tube 13 associated with the plate 12 on the lowermost pan 10 extend downwardly into the lower portion 5 of the tower casing, while those of each of the remaining tubes ex-

tend into and terminate below the oil or gasoline level in the next lower bubble pan, extending through the plate 12 on the rim of said pan. By these means the oil or gasoline 5 is maintained to the desired level in the bubble pans, and excess oil or gasoline is conducted downwardly from one pan to another and into the lower portion of the tower casing.

10 A pipe 15 communicates with the tower casing above the lower bubble pan in the enlarged upper portion 6, and this pipe is used to draw off "reflux" for further treatment or for being discarded, as the case may be.

15 A further pipe 16 enters the top of the tower casing for conducting gasoline or oil into the latter so that the desired temperature or "end point" may be maintained in the upper portion of the tower above the 20 bubble pans. This supply of oil or gasoline is also used to build up "reflux" in the apparatus, and mounted in the top of the tower casing is a perforated horizontal partition 17 which is spaced above the uppermost bubble 25 pan and below the outlet of pipe 16 so as to spread the gasoline or oil laterally as it passes from the pipe 16 into the tower.

The general operation is old and well understood in the art, and as the functions of 30 the novel features have been clearly pointed out above, further detailed description is believed unnecessary. However, it may be particularly noted that the ascending vapors are allowed to expand in the enlarged upper portion 6 of the tower, thereby enhancing the distilling operation and increasing the capacity of the tower. Moreover, the construction is extremely simple and durable, insuring efficient operation and economy in 35 manufacture. Still further, the spreading of the oil or gasoline introduced into the top of the tower enhances the condensing action at this point, and the foraminous covers for the bubble pans prevent excessive bubbling 40 and avoid entraining of undesirable substances in the ascending vapors.

45 Minor changes may be made without departing from the spirit and scope of the invention as claimed.

50 What I claim as new is:

1. In a bubble tower for dephlegmating hydrocarbon oil vapors, a bubble tray comprising a pan having apertures in the bottom thereof, inverted J-shaped vapor risers 55 mounted in said apertures and extending upwardly and then downwardly to points adjacent but above the bottom of the pan, a foraminous cover plate on the pan overlying the vapor risers, and means for conducting excess oil from the upper surface of the cover plate downwardly through the pan.

60 2. In a bubble tower for dephlegmating hydrocarbon oil vapors, a bubble tray comprising a pan having apertures in the bottom thereof, inverted J-shaped vapor risers 65

70 mounted in said apertures and extending upwardly and then downwardly to points adjacent but above the bottom of the pan, a foraminous cover plate on the pan overlying the vapor risers, means for conducting excess oil from the upper surface of the cover plate downwardly through the pan, said last named means embodying a tube mounted at its upper end in and extending from the cover plate through the pan and having downwardly diverging branches at its lower end adapted to enter a similar lower tray.

75 3. In a bubble tower for dephlegmating hydrocarbon oil vapor, a casing, a series of bubble trays arranged in vertically spaced relation within the casing, the bottom of each tray having apertures formed therein, a series of substantially J-shaped vapor risers 80 mounted in an inverted manner in said apertures on each tray, a perforated cover plate disposed over the inverted J-shaped vapor risers and adapted to rest on the upper edge of the rim of each tray, a vertically disposed tube fitted in a central opening formed in each cover plate, said tube extending downwardly through the bottom of the corresponding tray, branch pipes diverging from the lower end of each tube for disposition through the perforated cover plate of the subjacent tray, the lower ends of the branch 85 pipes terminating in spaced relation with respect to the bottom of the subjacent tray.

90 4. In a bubble tower for dephlegmating hydrocarbon oil vapors, a casing, a series of bubble trays arranged in vertically spaced relation within the casing, the bottom of each tray having apertures formed therein, a series of substantially J-shaped vapor risers 95 mounted in an inverted manner in said apertures on each tray, a perforated cover plate disposed over the inverted J-shaped vapor risers and adapted to rest on the upper edge of the rim of each tray, a vertically disposed tube fitted in a central opening formed in each cover plate, said tube extending downwardly through the bottom of the corresponding tray, branch pipes diverging from the lower end of each tube for disposition 100 through the perforated cover plate of the subjacent tray, the lower ends of the branch pipes terminating in spaced relation with respect to the bottom of the subjacent tray.

105 5. In a bubble tower for dephlegmating hydrocarbon oil vapors, a casing, a series of bubble trays arranged in vertically spaced relation within the casing, the bottom of each tray having apertures formed therein, a series of substantially J-shaped vapor risers 110 mounted in an inverted manner in said apertures on each tray, a perforated cover plate disposed over the inverted J-shaped vapor risers and adapted to rest on the upper edge of the rim of each tray, a vertically disposed tube fitted in a central opening formed in each cover plate, said tube extending downwardly through the bottom of the corresponding tray, branch pipes diverging from the lower end of each tube for disposition 115 through the perforated cover plate of the subjacent tray, the lower ends of the branch pipes terminating in spaced relation with respect to the bottom of the subjacent tray, a heated oil inlet pipe extending into the side of the casing at the lower end thereof, an excess oil drain pipe extending from the bottom portion of the casing, an oil inlet pipe 120 extending into the top of the casing, and a perforated spreader plate arranged horizontally in the top portion of the casing, and a reflux conducting pipe extending from the intermediate portion of the casing adjacent one of the trays.

125 In testimony whereof I affix my signature.

130 WILLIAM E. TETER.
